Maurice Block

UNITED STATES PATENT OFFICE.

LEON LOBEL, OF NEW YORK, N. Y.

ARCH-SUPPORT.

1,229,300.

Specification of Letters Patent. Patented June 12, 1917.

Application filed July 21, 1916. Serial No. 110,498.

To all whom it may concern:

Be it known that I, LEON LOBEL, a citizen of the United States of America, residing at New York city, county and State of New 5 York, have invented certain new and useful Improvements in Arch-Supports, of which the following is a full, clear, and exact description.

This invention relates to improvements 10 in arch-supports, and pertains more particularly to an auxiliary or supplemental yieldable supporting element designed to act in coöperation with the yieldable elements of an arch-supporter, which in turn are arranged to perform a kneading or massaging effect during the ambulatory movements of the wearer. My present invention is intended to improve the construction of arch-supporters described in United States Letters 15 Patent No. 1,129,039, dated February 16, 1915, and my invention consists, generally speaking, of a yieldable element or spring interposed between the base-plate and alining element contacting with the yieldable 20 fingers which carry the covering or pad, the said yieldable element being arranged to be compressed and expand during the ambulatory movements of the wearer, rather than to swing. I am thus able to provide a 25 stiff but yieldable support for a broken down arch which is better adapted to cushion shocks than a spring which is secured at one end thereof to the base-plate the free end of which is free to swing. A further object 30 of my invention is to provide a special construction of the yieldable element or spring hereinabove referred to and means to permit adjustment thereof on the base-plate, for a purpose which will be hereinafter 35 described.

I will now proceed to give a detailed description of my invention in connection with the accompanying drawing, forming part hereof, wherein—

40 Figure 1 is a plan view of my improved arch-supporter, partly broken away to show the yieldable elements;

45 Fig. 2 is an enlarged cross-sectional view, the section being taken on a line 2—2 in Fig. 1;

50 Fig. 3 is a fragmentary side view looking in the direction of the arrow in Fig. 2.

Referring to the drawing, the supporter

comprises a base-plate 1 shaped to fit the sole of a shoe, 2 indicating a yieldable supporting element consisting of a plurality of independently yieldable fingers 3 carried by a plate 4 secured at 5 to the plate 1. The fingers 3 are shaped in such contour as to fit the arch of a foot and support the same. 60 The fingers 3 are covered by a pad 6 of leather or the like, which is secured to the plate 1 by rivets 7. To assist the fingers 3 to perform their function I provide a yieldable alining plate 8 which is fitted to 65 the contour of the fingers 3, the said plate being secured at 9 to certain of said fingers, the ends 10 of the said plate being unsecured and adapted to slide upon the plate 1.

The supplemental bracing device referred 70 to consists of a coil spring 11 (Figs. 1, 2 and 3) interposed between the alining-plate 8 and base plate 1 in such manner as to be compressed when weight is imposed thereon. The spring 11 may be secured to the alining 75 plate by a rivet 12 at one end thereof, the lower end thereof resting unsecured in contact with the plate 1. As the alining plate 8 rises and falls during the ambulatory movement of the wearer, the spring 11 will be 80 compressed and extend longitudinally thereof. A spring of this formation is far more durable, for the purposes of its present use, than a flat leaf-spring, besides being adapted to yieldably support the alining plate 8. 85 Furthermore, a coil-spring will recover or rebound, after shock, much more quickly and with more snap than a leaf-spring; hence, the kneading or massaging effect desired is more thoroughly accomplished. 90

Having now described my invention, what I desire to secure by Letters Patent is:

1. In an arch-support, the combination of a base-plate and a series of arch-supporting fingers, with an alining plate arranged transversely to said fingers and attached thereto also curved above said plate and a coiled supporting spring interposed between said base-plate and said alining plate and consisting of a series of superposed convolutions, the uppermost convolution being attached to said alining plate, in order that the swinging of said spring may be prevented. 100

2. In an arch-support, the combination of a base-plate and a series of arch-supporting fingers, with an alining-plate arranged

transversely to said fingers and attached thereto, also curved above said base plate and a spiral supporting spring interposed between said base-plate and said alining-
3 plate and attached at its upper end to the latter in order that the swinging of said spring may be prevented.

Signed at New York city, N. Y., this 19 day of July, 1916.

LEON LOBEL.
